GEORGE R. CORNWALL, OF RYE, NEW YORK, ASSIGNOR, BY MESNE ASSIGNMENTS, TO
JAMES G. COFFIN, TRUSTEE.

PROCESS OF PRODUCING PRINTING-SURFACES AND PRINTING-FORMS.

1,127,737.

Specification of Letters Patent.

Patented Feb. 9, 1915.

Application filed April 11, 1906, Serial No. 311,084. Renewed July 18, 1914. Serial No. 851,818.

To all whom it may concern:

Be it known that I, GEORGE R. CORNWALL, a citizen of the United States, residing at Rye, in the county of Westchester and State 5 of New York, have invented new and useful Improvements in Processes of Producing Printing-Surfaces and Printing-Forms, of which the following is a specification.

The invention relates to the printing art 10 and more especially to the production of printing surfaces.

Objects of the invention are to provide a new and useful method for producing such surfaces.

15 Other objects of the invention will in part be obvious and will in part appear or be particularly pointed out in the specification and the claims.

The invention consists in the novel processes, and improvements herein shown and described.

The accompanying drawings, referred to herein and forming a part hereof, illustrate one way of carrying out certain steps of the 5 process included by the invention.

Of the drawings: Figure 1 illustrates an impression-receiving surface; Fig. 2 indicates a form comprised of interchangeable composition units in the form of line bars 10 adapted for use with this invention; Fig. 3 illustrates one manner of impressing lines of characters upon the sensitized surface of line bars by the action of light and also the registering of the lines of characters with 15 the bars. Fig. 4 illustrates the impressing of lines of characters upon light-sensitive line bars by artificial light; Fig. 5 shows a form of interchangeable composition units, said units being in the form of line bars,

20 after development; Fig. 6 shows one manner of impressing lines of characters from a form composed of line bars upon a plate by the action of light; Fig. 7 shows a printing plate which has been prepared for printing, and impressions being taken therefrom for proof-reading or other purposes; Fig. 8 shows a proof sheet with an indicated correction; Fig. 9 shows a corrected line bar; Fig. 10 shows the form after the corrected bar has been substituted for the incorrect bar; Fig. 11 shows one manner of impressing lines of characters from a form composed of line bars upon a plate by the action of light and illustrates further the

making of a permanent printing plate after 55 the desired changes have been made in the form; and Fig. 12 illustrates a printing surface or printing plate.

The invention contemplates the producing of printing surfaces for letter-press 60 matter by means of interchangeable composition units which are adapted to have a printing or character-impressing function by the action of light and provides a form embodying such units and a process of producing a printing surface by the use of such units.

The invention in some of its aspects contemplates using composition units of various kinds.

In certain other aspects the invention contemplates the use of composition units in the form of line bars.

In certain of its aspects the invention contemplates the use of composition units 70 effecting their printing or impressing function by the action of light generally.

In other aspects of the invention composition units are contemplated of a light-transmitting material and which bear one 80 or more characters upon a surface, the characters and the surrounding surface possessing different properties with respect to the transmission of light, the characters being thereby defined by the surrounding surface.

By certain features of the invention it is also contemplated to make use of interchangeable composition units for the purpose of making desired changes, such as 90 corrections, additions, eliminations, or transpositions, of the said units in order to bring the composed matter into the desired final form.

According to one feature of the invention 95 it is contemplated furthermore to use line bars of any character whatsoever, by this feature of the invention the imposition of the lines of characters upon the line bars by the action of light being contemplated 100 whether the bar itself obtains its printing or impressing function by the action of light or otherwise.

The invention possesses other features and aspects besides those pointed out above.

In the accompanying drawings which, as hereinbefore indicated, illustrate one manner of carrying out certain steps of the invention

and one embodiment of the form produced by the invention, composed matter is shown as being primarily impressed in a series of justified lines of characters upon an impression-receiving surface 1, which surface in certain aspects of the invention may be of any nature but in certain other aspects is of a light-transmitting nature, the characters being placed thereon in an opaque or light-arresting medium, such for instance as an opaque ink. It will be found that certain papers are of sufficiently uniform texture and transmit light sufficiently freely and uniformly to act as the impression-receiving surface, although other suitable impression-receiving surfaces may be used. A series of composition units which, as previously stated, are herein shown as line composition units or line bars, are assembled into a form 2. Prior to the assembling of the bars into the form, or subsequent to such assembling, as may be found desirable or convenient, the surfaces of the bars are sensitized in a suitable manner so as to adapt them to receive an imprint or impression by the action of light. This may be done, for instance, by applying a sensitive coating to the surface of the bars containing a light-sensitive agent, such as a silver salt, a chromic salt, or sensitive asphalt, or other suitable agent of the required nature. For convenience in holding the form of line bars together suitable holding means are provided, a form thereof being herein shown as comprising a chase 3. The chase is further shown as provided with suitable means for engaging, holding and releasing the line bars, the illustrated form of such means being indicated generally by the reference numeral 4. While, according to certain features of the invention, the line bars may be of various kinds or natures, according to other features of the invention, as previously indicated, it is contemplated to use line bars of a light-transmitting material, such as glass, or other suitable material. It is desirable to position the impression-receiving surface 1 and the form of line bars so that each line of characters upon the surface 1 will be placed in definite relation to a line bar and the different lines of characters will be transferred or impressed upon their corresponding line bars in definite relation in order to produce a uniform arrangement of the matter upon the final printing surface, as well as for other purposes. To accomplish this end, suitable registering devices are provided in connection with the impression-receiving surface 1 and the form of line bars 2, said devices co-acting together to effect the desired function as above set forth. As illustrated in the drawings such registering means are shown in definite relation to each line of characters upon the impression-receiving surface and also in definite relation to the composition units in the form. The said registering means are further shown upon the impression-receiving surface 1 as in definite relation to each end of each line of the justified lines of characters carried upon the said impression-receiving surface, and devices for co-operating therewith are shown as being in definite relation to each end of each of the line bars, although it will be understood that in certain aspects of the invention any suitable registering means may be employed. As illustrated herein the registering means carried by the impression-receiving surface 1 consist of perforations 5 and the particular form of co-operating registering devices which are in definite relation to the line bar as shown as pins 6 carried by the chase 3. It will now be obvious that if the impression-receiving surface 1 be imposed upon the surface of the form of line bars 2 that the perforations 5 passing over the pins 6 will bring each line of characters into definite relation to a line bar in the form. Any suitable means for causing the light to act upon the said surfaces so as to impress the lines of characters carried by the impression-receiving surface 1 upon the line bars of the form 2 may be employed and in Fig. 4 of the drawings a source 7 of artificial light is shown as being employed for this purpose.

After the light has acted upon the sensitive surface of the form of bars 2, the bars are then developed, the developing process being of a nature corresponding to the sensitizing agent used upon the surface of the bars. With a surface sensitized by one of the silver salts many different developers may be used which are well known in the art; with a chromated colloid it is customary to develop with either warm or cold water, depending upon the results which it is desired to effect; and with sensitive asphalt it is common to develop with turpentine. The particular mode of developing will be suited to the sensitive surface used and merely as such forms no part of the present invention. The bars may be developed in the form, or singly, as may be desirable or convenient. In Fig. 5 of the drawings herewith the bars are shown as having been developed, the characters and the surrounding surface of the bar having different properties with respect to the transmission of light. As shown in the said figure, the characters have remained light transmitting and the surrounding surface has been made light arresting.

It is contemplated by the invention, with line bars, or other composition units, that effect the printing or impressing function by the action of light, to sensitize a unitary plate in order to secure a printing surface

from the line bars by the action of light upon the sensitive surface of the plate. It is generally found in practical work, however, that considerable change is necessary in letter-press composed matter before it is in the desired final form and it is desirable to make all these changes before the final printing surface is secured. With this object in view the present invention contemplates as one of its features providing proof sheets wherein corrections and such other changes as it may be desired to make may be indicated, and the line bars or other composition units may then be changed so as to bring the composed matter into the desired final form prior to the production of the final printing surface. If desired, the proofs may be taken upon a sensitive paper direct from the form 2, but in practical work, if desired, a plate may be provided, which may be styled the temporary plate, from which a practically unlimited number of proof impressions may be pulled. Accordingly, certain features of the invention contemplate the securing of proof impressions and according to certain further features of the invention the securing of a temporary plate which may be inked and proof impressions upon ordinary paper in printers ink secured therefrom is contemplated. One manner of carrying out such a series of steps is shown in the drawings.

Fig. 6 of the drawings may be taken to illustrate the impressing of the composed matter carried by the form of bars 2 upon any suitable surface, whether of sensitized paper for proof sheets direct, or a printing plate which is to be used as a temporary proof plate, or a final unitary printing plate. The chase 3 is shown as placed in juxtaposition to a source of artificial light 7 and having a plate 8 in contact therewith. It will be understood that the surface of the plate 8 will be sensitized in a suitable manner, as in one of the ways hereinbefore set forth. The plate 8 may then be developed and otherwise prepared in a suitable manner, inked and proof impressions 9 taken therefrom in any desired number. As illustrating one operation frequently necessary in bringing the composed matter into the desired final form, the sheet 9 is shown as containing a typographical error, indicated thereon in suitable manner at the point 10. The corresponding line bar in the form 2, see Fig. 5, is indicated by the reference numeral 11. A new line bar 12 will be made, which may be made substantially as above set forth, in which the error has been eliminated, and the said bar is then substituted for or interchanged with the bar 11 in the form 2. The said corrected bars may be produced in series as well as the original composition, when a sufficient number of changes are made, and changes other than

corrections, such as additions, transpositions, or eliminations of matter, can be made in substantially the same manner in the form of bars in order to bring the composed matter into the desired final form.

In Fig. 10 of the drawings the chase 3 is shown with the correct bar 12 substituted for the incorrect bar 11 therein. The form of bars, now carrying the matter in the desired final form, is used to impress a printing plate in order to secure the final printing surface desired. According to certain features of the invention it is contemplated to produce the final printing plate by the action of light. A suitable printing plate, such as the plate 13, which may be of metal or other suitable substance, is provided, and the surface thereof sensitized. Said sensitizing may be carried out in one of the ways above described in connection with the sensitizing of the surface of the bars, or in any other suitable way. Where the said plate 13 is intended for providing a planographic printing surface, it is generally of zinc or aluminum, the surface of which has received suitable preliminary treatment, as by graining, although a stone could be used, if desired. As shown in Fig. 11 of the drawings, the plate 13 is subjected to the action of light from the source 7 through the surface of the bars in the form 3. The surface of the plate is then developed, and this may be done in substantially the manner set forth above in connection with the developing of the surface of the planographic line bars, or any other suitable manner, and the surface of the plate is then prepared for printing. With a planographic plate this is done by etching, gumming and rolling up with ink in a well-known manner.

From all the foregoing it will be understood that a novel and useful method of producing a printing surface has been provided and a novel and useful printing form has also been provided which realize the objects of invention and advantages herein set forth, together with other objects and advantages.

The invention, in its broader aspects, is not limited to the particular manner of carrying out the steps comprised in the method, nor to the particular embodiment of the printing form, as variations may be made in these without departing from the principles of the invention.

What I do claim as my invention and desire to secure by Letters Patent, is:

1. The process of producing a letter-press printing plate which comprises placing a line of characters upon an impression-receiving surface, placing a registering mark in definite relation to the said line, sensitizing the surface of a line bar, positioning the line of characters with reference to the line bar by means of said registering mark, im-

pressing the line of characters upon the sensitized surface of the line bar, and developing the said surface of the line bar.

2. The process of producing a letter-press printing plate which comprises placing a series of justified lines of characters upon an impression-receiving surface, sensitizing the surface of a plurality of line bars, assembling the said bars into a form, bringing the said impression-receiving surface and the form of line bars into such relative position that each line of characters upon the impression-receiving surface will be in register with a line bar in the said form, impressing the lines of characters upon the sensitized surface of the bars, and developing the said surface of the bars.

3. The process of producing a letter-press printing plate which comprises placing a series of justified lines of characters upon an impression-receiving surface, sensitizing the surface of a plurality of line bars, assembling the said bars into a form, bringing the said impression-receiving surface and the form of line bars into such relative position that each line of characters upon the impression-receiving surface will be in register with a line bar in said form, impressing the lines of characters upon the sensitized surface of the bars by the action of light, and developing the said surface of the bars.

4. The process of producing a letter-press printing plate which comprises placing a series of justified lines of characters upon an impression-receiving surface, sensitizing the surface of a plurality of line bars, assembling the said bars into a form, bringing the said impression-receiving surface and the form of line bars into such relative position that each line of characters upon the impression-receiving surface will be in register with a line bar in the said form, impressing the lines of characters upon the sensitized surface of the bars by the action of light, developing the said surface of the bars, preparing the surface of a unitary printing plate so that it will be in condition to be impressed by the said line bars, and then impressing the lines of characters from the said line bars upon the surface of the printing plate.

5. The process of producing a letter-press printing plate which comprises placing a series of justified lines of characters upon an impression-receiving surface, sensitizing the surface of a plurality of line bars, assembling the said bars into a form, bringing the said impression-receiving surface and the form of line bars into such relative position that each line of characters upon the impression-receiving surface will be in register with a line bar in the said form, impressing the lines of characters upon the sensitized surface of the bars by the action of light, developing the said surface of the bars.

bars, sensitizing the surface of a unitary planographic printing plate, and impressing the lines of characters from the said bars upon the said plate by the action of light.

6. The process of producing a letter-press planographic printing plate which comprises placing a series of justified lines of characters upon an impression-receiving surface, sensitizing the surface of a plurality of line bars, assembling the said bars into a form, bringing the said impression-receiving surface and the form of line bars into such relative position that each line of characters upon the impression-receiving surface will be in register with a line bar in the said form, impressing the lines of characters upon the sensitized surface of the bars by the action of light, developing the said surface of the bars, sensitizing the surface of a unitary planographic printing plate, impressing the lines of characters from the said bars upon the said plate by the action of light, and preparing the said plate for printing planographically.

7. The process of producing a letter-press printing surface which comprises placing a series of lines of characters upon an impression-receiving surface, sensitizing the surface of a plurality of line bars, assembling the said bars into a form, bringing the impression-receiving surface and the form of line bars into such relative position that each line of characters upon the impression-receiving surface will be in register with a line bar in the said form, impressing a line of characters upon the sensitized surface of the bars by the action of light, developing the said surface of the bars, making a proof impression from the said bars, and making a printing plate from the said bars.

8. The process of producing a letter-press printing surface which comprises placing a series of lines of characters upon an impression-receiving surface, sensitizing the surface of a plurality of line bars, assembling the said bars into a form, bringing the impression-receiving surface and the form of line bars into such relative position that each line of characters upon the impression-receiving surface will be in register with a line bar in the said form, impressing a line of characters upon the sensitized surface of the bars by the action of light, developing the said surface of the bars, making a temporary printing plate from said bars, taking proof impressions from said temporary printing plate, making such changes as may be desired to bring the composed matter carried by the said bars into the desired final form, sensitizing the surface of a unitary printing plate, transferring the lines of characters from the said form of bars to the printing plate, and developing the printing plate.

9. The process of producing a letter-press

- printing surface which comprises placing lines of characters constituting composed matter in definite relation upon line bars by the action of light, making such changes by 5 way of correction or otherwise in such line bars as may be necessary to bring the composed matter into the desired final form, transferring the characters from the said line bars to a unitary plate, and preparing 10 the said plate for printing.
10. The process of producing a letter-press printing surface which comprises placing lines of characters constituting composed matter in definite relation upon line 15 bars by the action of light in such manner as to render the character-bearing surface of the line bars light transmitting and light arresting so as to define the characters in the surrounding surface, sensitizing a unitary printing plate, and transferring the lines of characters from the said line bars to the printing plate by the action of light.
11. The process of producing a letter-press printing surface which comprises assembling a series of line bars of light-transmitting material into a form, sensitizing a surface of the said line bars, imposing lines of characters upon the said line bars by the 20 action of light, sensitizing the surface of a printing plate, transferring the lines of characters from the said line bars to the surface of the said plate by the action of light, and preparing the said plate for printing.
12. The process of producing a letter-press printing surface which comprises assembling into a form a plurality of character-bearing composition units adapted to 25 make impressions by the action of light in such order as to represent a composition, making a proof impression from the said 30 form, making such changes in the composition units as may be desired to bring the composed matter into its final form, sensitizing the surface of a printing plate, impressing the composed matter from the said character-bearing units upon the surface of the plate by the action of light, developing the surface of the plate, and preparing the same for printing.
13. The process of producing a letter-press printing plate which comprises placing a line of characters upon an impression-receiving surface, placing a registering device in definite relation thereto, sensitizing a line bar, placing said line bar and a registering device in definite relation, bringing the line of characters and the line bar into register by means of said registering devices, and impressing the line of characters upon the surface of the bar by the action of light.
14. The process of producing a letter-press printing plate which comprises placing a line of characters upon an impression-receiving surface, placing a registering device in definite relation thereto, sensitizing a composition unit, placing said composition unit and a registering device in definite relation, bringing the line of characters and the composition unit into register by means of said registering devices, and impressing the line of characters upon the surface of the composition unit by the action of light.

In testimony whereof I have signed my name to this specification in the presence of two subscribing witnesses.

GEORGE R. CORNWALL.
